H. PIKE

FOLDING IRONING BOARD

Filed Feb. 27, 1922

Patented May 22, 1923.

1,456,193

UNITED STATES PATENT OFFICE.

HERBERT PIKE, OF CHICAGO, ILLINOIS.

FOLDING IRONING BOARD.

Application filed February 27, 1922. Serial No. 539,350.

To all whom it may concern:

Be it known that I, HERBERT PIKE, a subject of the King of Great Britain, residing at Chicago, in the county of Cook and State 5 of Illinois, have invented certain new and useful Improvements in a Folding Ironing Board, of which the following is a specification.

This invention relates, generally, to ironing boards, but particularly to that type of such boards in which the parts thereof can be folded together, so as to occupy but little space when not in use, or when it is desired to ship the same, and it consists in certain 15 peculiarities of the construction, novel arrangement and combination of the various parts thereof, as will be hereinafter more fully set forth and specifically claimed.

One of the important objects of the invention is the provision in an ironing board of means whereby the board or garment-support thereof shall be pivotally mounted near one of its ends on a pair of supporting legs and detachably supported near its other 25 end on another pair of such legs, in such a way, that one end of the board, say the front end thereof, can be readily detached from its support, thus permitting the board to be turned on a pivot so as to assume and 30 maintain an inclined position downwardly from its front end, so that it will be unnecessary, for the user of the board, to employ either hand to hold the board away from the front pair of legs or in an inclined 35 position, but so that the user can employ both hands in placing and adjusting a garment, such as a skirt or the like, over and around the inclined board, after which, the front part of the board can be depressed 40 and caused to engage its support and be ready for use.

Another object is to provide means for automatically elevating the board from its normal position.

Still another object is to provide simple and efficient means for automatically fastening the board to its detachable support, yet so that it can be readily released therefrom.

Other objects and advantages of the invention will be disclosed in the following description and explanation.

In the accompanying drawing, which serves to illustrate an embodiment of the invention—

Fig. 1 is a view in side elevation showing the parts by continuous lines in their nor-

mal or operative positions and illustrating by dotted lines some of the parts in the act of being folded towards the board, as well as the raised position of the board. 60

Fig. 2 is an enlarged bottom plan view taken on line 2—2 of Fig. 1 showing the means for detachably securing the front pair of supporting legs to the front portion of the board. 65

Fig. 3 is an enlarged sectional view taken on line 3—3 of Fig. 2 looking in the direction indicated by the arrows.

Fig. 4 is a rear end view of the board and a portion of the supporting legs therefor. 70

Fig. 5 is a detached perspective view of one of the locking or securing braces of the support, and Fig. 6 is a bottom plan sectional view taken on line 6—6 of Fig. 4 showing the springs and their associated parts for actuating the ironing board. 75

Corresponding numerals of reference refer to like parts throughout the different views of the drawing. 80

The board or support for garments is designated by the numeral 8 and may be of any suitable size, form and material, but preferably elongated and having one of its ends tapered as is clearly shown in Fig. 2 of the drawing. The rear portion of the board 8 has transversely mounted thereon at a suitable distance from its rear end a bracket 9 which has at each of its ends a depending member 10 to each of which is pivotally secured the upper end of a supporting leg 11 which legs are spaced apart and held in such position by means of brace bars 12—12 and 13, one of the bars 12 being located transversely on the upper portion of the pair of supporting legs 11 and the other bar 12 similarly disposed on the lower portion of said legs, while the bar 13 is diagonally arranged with respect to said legs. The legs 11 as well as the body 9 of the bracket are by preference made of angle iron. 90

Mounted longitudinally on the lower surface of the rear portion of the board 8 and in parallelism with one another are a pair of substantially U-shaped guiding and locking members 14 for a yoke 15 which lies across the members 14 and between the same and the lower surface of the board, as will be readily understood by reference to Figs. 1 and 4 of the drawings. This yoke 15 has its arms 16 connected to the upper brace bar 12 by means of coil springs 17 within the coils 105 110

of which springs the said arms are by preference extended. Each of the guide members 14 is provided in its upper edge near its rear end with a notch or recess 18 to receive the 5. yoke 15 in such a way as to cause the tension of the springs 17 to be exerted on said members and the rear end of the board so as to automatically depress the said end of the board when its front portion is released.

10. Near its front end the board 8 has transversely mounted on its lower surface a piece of angle iron 19 which has its ends turned inwardly as at 20 to form a socket for the upper end of the front supporting legs 21

15. which are spaced from each other and connected together at their upper ends by a cross-piece 22 of a size to fit between the in-turned ends 20 of the socket. The legs 21 as well as their connecting portion or cross-piece 22 are by preference made of angle iron. At about its middle the vertically disposed wall of the connecting portion 22 of the legs 21 is provided with a recess 23 for the reception of a locking pin 24 which is 25. carried by a leaf or flat spring 25 secured at one of its ends to the front surface of the socket near one of its ends. This spring extends horizontally along the socket and has its free end turned outwardly therefrom to 30. provide a handle 26 or thumb-piece for disengaging the lock pin 24 from the cross-bar or portion 22 of the front legs. The lock pin 24 is upwardly beveled as shown at 27 in Fig. 3, so that when the board 8 is pressed 35. downwardly so as to cause the socket to receive the upper portion of the legs 21, the upper surface of the part 22 will strike the beveled portion 27 of the locking pin 24 and thus cause said pin and its spring to be 40. moved outwardly until the recess 23 in the part 22 registers with said pin, when it is apparent it will be caused by the action of the spring 25 to automatically engage the portion 22 of the front legs and thus hold 45. the board securely in place thereon.

Extending longitudinally with the board and in parallelism with one another are connections 28 each of which comprises two pieces 29 the adjacent ends of which are 50. pivotally connected together and the outer ends of which are pivotally secured to the lower portions of the front and rear supporting legs, as will be understood by reference to Figs. 1 and 4 of the drawing. Pivotally secured at its lower end to each of the rear portions 29 of each of the connections 28 is a jointed bracket 30 the upper end of each of which is pivotally secured to one of the legs 11 near its upper end.

60. Pivotally secured at its lower end to each of the front portions 29 of the connections 28 is a jointed brace 31 the upper end of each of which is pivotally secured to one of the front legs 21 above its middle.

65. By reference to Fig. 5 which is shown as

representing a detached view of one of the jointed braces 30, but which may represent one of the jointed braces 31, as they are of the same construction, it will be observed that said braces are made of two pieces 32 70 and 33 which are pivotally connected together at their adjacent ends by means of a bolt passing through openings 34 in said pieces. The portion 33 of each of the braces is provided with a recess 35 to receive a 75 laterally extending lug or projection 36 on the lower end of the portion 32 thus locking the two parts together and preventing downward movement thereof.

From the foregoing and by reference to the drawing, it will be seen and clearly understood that by moving the braces 30 and 31 as well as the connections 28 upwardly at their joints and by disconnecting the legs 21 from the front portion of the board, which may be done by pressing the handle portion 26 of the spring 25 outwardly so as to withdraw the pin 24 from locking engagement with the part 22 of the front legs, the supporting parts may be folded together and against the board, thus occupying a limited amount of space when the board is not in use or when it is desired to ship the same. It will be further understood that by pressing the braces 30 and 31 as well as the connections 28 downwardly at their joints, the braces will be locked against further downward movement by reason of the engagement of the lugs 36 with the recesses 35 of the members of said braces.

Assuming the parts of the device to be in the position illustrated by continuous lines in Fig. 1 and it is desired to place a garment such as a skirt or petticoat over and around the board 8 to be ironed, all that is necessary, is to press the handle 26 of the spring 25 forwardly, which operation will release the socket from the upper portion of the front supporting legs and allow the springs 17 of the yoke 15 to exert their tension through said yoke and the guide members 14 against the rear end of the board 8, thus causing it to be tilted to about the position shown by dotted lines in Fig. 1 and to be maintained in such position, when it is apparent that the garment can be placed over the free end of the board, after which the board can be pressed downwardly at its front end thus causing the upper portion of the legs 21 to be automatically engaged by the socket and its locking pin.

In folding the parts of the table, after the connections 28 and braces 30 and 31 have been moved upwardly at their joints, it is manifest that the legs 21 can be released from the socket, when said legs can be moved towards the legs 11 in which operation the legs 11 may be tilted rearwardly a slight distance which will cause the yoke 130

15 to dis-engage the notches 18 in which dis-
engaged position said yoke can be main-
tained by turning the table bottom upwards
or by placing the board with its rear end
5 downwardly, thus enabling the parts to be
folded to about the positions shown in
dotted lines in Fig. 1 without interference
by the yoke 15 engaging the locking re-
cesses in the guide members 14 therefor.

10 Having thus fully described my inven-
tion, what I claim as new and desire to se-
cure by Letters Patent is—

In a device of the class described, the com-
bination with a supporting frame including

a pair of front supporting legs and a pair 15
of rear supporting legs, of an ironing-
board mounted on said rear legs for tilting
movement and adapted for detachable en-
gagement with the upper portion of said
front legs, a guide member having a recess 20
in its upper surface longitudinally mount-
ed on the lower surface of the rear portion
of said board and spaced therefrom, a
spring-actuated yoke mounted on the up-
per portion of the rear legs astride said 25
guide member and normally in engagement
with its recess.

HERBERT PIKE.
